UNITED STATES PATENT OFFICE.

GEOGE M. STEDMAN, OF AURORA, INDIANA, ASSIGNOR TO STEDMAN'S FOUNDRY & MACHINE WORKS, OF AURORA, INDIANA, A CORPORATION OF INDIANA.

REVOLVING SCREEN.

Application filed April 19, 1922. Serial No. 555,552.

To all whom it may concern:

Be it known that I, GEORGE M. STEDMAN, a citizen of the United States, and residing at Aurora, in the county of Dearborn and State of Indiana, have invented a new and useful Improvement in Revolving Screens, of which the following specification is a full disclosure.

This invention relates to tapper mechanism construction and operation as applied to screening drums, of a type wherein the substance to be screened or sifted is placed, and the drum rotated to accomplish a sifting operation.

This invention relates to improved tapper mechanism construction and operation, and to the construction of the screen supporting frames forming when assembled the screening drum used in conjunction with said tapper mechanism. These drums are usually of hollow prismatic regular polygonal configuration, and, are formed of a series of spiders mounted immovably upon a shaft to which spiders, are attached frames, covered with wire screening of the desired mesh. Baffles are generally, suitably arranged at the interior of the drums to cause the material to be raised and dropped upon the lowermost faces of the screen walls. The adherence of the substance being screened, within the interstices of the screen material at the interior of the drum prevents the proper functioning of the "screen," and much difficulty has been experienced in thoroughly loosening the adhered substance therefrom throughout the entire area of the screen walls.

An object therefore of the invention is to percussively vibrate the drum walls to loosen the adhered substance, this object being furthered by successively tapping or striking and vibrating each wall throughout its entire area while the wall is in its uppermost or substantially horizontal position, the vibrative blows being delivered with predetermined frequency during each cycle of rotation of the drum.

Another object is the provision of screen frame units so constructed that each screen stretched thereacross will be thoroughly vibrated throughout its entire area when percussive blows are delivered indirectly thereagainst, by the improved adjustable tapper mechanism herein disclosed.

Another object is to vibrate each screen

wall in its uppermost position, thus utilizing the action of gravity in conjunction with such vibration to thoroughly loosen the adhered substance throughout the entire screen area and cause it to fall to the lower side 60 of the drum.

Another object is to provide means whereby the vibrative effects of the blows of the tapper arms will be positively transmitted to and throughout the entire area of the 65 screen, although the blows may not be delivered at the exact center of a given screen, this object being accomplished by delivering the blows to metal strips aligned circumferentially in rotative planes, each strip being 70 connected at its midpoint to a ridge-bar placed centrally and longitudinally of each screen and extending the entire length thereof, the blows of the tapper arms being delivered to the metal strip and the vibrative ef- 75 fects carried or transmitted to the bars and then centrally distributed to the screen. Thus, when a tapper arm vibrates after its initial blow the arm will continue to strike some portion of the strips although the 80 drum may have rotated, after such blow has been delivered. At whatever point, or points, the tappers may strike the strips the percussive effects will be transmitted and distributed centrally of and to the screen at 85 which point the vibrative effects are most effective.

Another object is to provide for varying the intensity of the whip-like blows delivered by the tapper arms.

Another object is to simultaneously strike a plurality of strips upon a given drum wall by means of a corresponding number of tapper arms mounted upon a single shaft and operated automatically by and conformably 95 to the rotation of the drum.

Other objects and certain advantages appear in a description of the drawings, forming a part of this specification, and reference is made to said drawings, in which:—

Figure 1 is a side elevation of one form of screening machine, the side walls of the same being broken away to show my improved screening drum formed of a plurality of screen frame units constructed in accordance with this invention and showing my improved tapper mechanism operable in conjunction therewith.

Figure 2 is an end view, partly in section, illustrating the improved screen frame con-

100

struction applied in the formation of a screening drum.

Figure 3 is a fragmentary end view of Fig. 1, showing in full and dot-and-dash lines the tapper-mechanism action and adjustment.

The numeral 1 generally designates a type of machine technically known as a "screen," comprising a suitably enclosed frame structure within which, and mounted lengthwise thereof for rotation, is a drum 2 which, in this instance, comprises screen frames of improved construction, over which frames is stretched the screening material 3 of any suitable mesh. The drum is supported longitudinally of its central axis by a shaft 4, slantingly mounted in bearings 5 and 6, said bearings being carried upon cross frames 7 and 8, and said shaft and drum being rotatable by any suitable means indicated at 9. The substance to be screened is introduced at the upper end, interiorly of the inclined drum through a hopper 10, a portion of the substance passing through the screen and the residue being discharged at the lower end of said drum by gravity.

The improved drum frame-units are identical in construction and the detailed description will therefore be directed to a single frame.

A plurality of spiders 12 are disposed upon and spaced lengthwise of the shaft 4, each spider, in this instance, providing six radial arms, the corresponding arms of each of the spiders being connected together by longitudinal angle irons 13 to form a drum base upon which the frame units are mounted, and suitably fastened.

Each frame unit comprises two rectangular frame sections of equal area, a base section 14 over which the screening material 3 is initially stretched and fastened, and an outer clamping section 16 attachable to said base section over the screening material. The sections are provided with centrally disposed longitudinal strips or bars, respectively 17, 18, between which the screen is also clamped when the frames are fastened together. The ridge-bar 18 is of greater depth than the bar 17 and extends outwardly, and beyond the plane of the outer section 16, forming a ridge, crosswise of which are disposed yieldable strips 20, herein denominated anvil-strips preferably of spring steel, fastened at their mid-positions to the ridge-bar 18 and, at their opposite ends, to the parallel longitudinal members of the section 16. The ridge bar 18 is fastened to the end rails of its frame and intermediate to flexible cross strips 20 of arched form. The spring steel bowed strips hold the bar 18 in suspension, and the bar in turn holds the screen fabric to prevent injury of the fabric or any bagging of the same. A suitable number of such anvil strips are pro-

vided, in this instance three, suitably spaced apart throughout the length of each frame unit. The corresponding anvil-strips of all frame units, when attached to the drum base, are circumferentially aligned in plane 70 of rotation of the drum to insure the engagement of the tapper arms therewith. Although the tapper arms may first strike the strips directly over the ridge-bars, since the drum continues its regular forward movement while the tapper arm continues to vibrate, the subsequent tappings of the arm may be at one side or the other of the ridge, and would, but for my improved anvil-strips, strike directly upon the screen, causing injury thereto. As will be readily apparent, the effects of the tapper blows are herein distributed or transmitted by the anvil-strips to the ridge-bars, to the screens midway thereof, and thence throughout 85 their entire area. The tapper arms 20^a, one arm for each circumferential row of anvil-strips, are rigidly but adjustably mounted upon a shaft 21, held in suitable bearings 22 at one side of and above the drum 2, and the shaft, and arms thereon, are operated simultaneously to give springing whip-like or percussive blows to the anvil strips 20 when any given drum face is in its uppermost position. The tapper arm shaft 21 at one end 90 and outside of the screen enclosure is provided with a trip-arm 24 rigidly but adjustably mounted thereon, its outer end 25 being engageable with the stepped teeth 26 of a trip-wheel 27 rigidly mounted upon the shaft 4, the teeth of said wheel corresponding to and being equal in number with the drum faces, or of such a number as will act to control the periodicity and number of blows indirectly delivered against and at the 105 uppermost surface of either a poly-faced or cylindrical drum "screen" at each cycle of revolution thereof. The teeth are so related to the drum faces that the trip-arm 24 will be raised and allowed to fall, (see Fig. 110 3), imparting motion to the tapper arms 20^a, causing the same to give the snapping whip-like blows to the strips 20, for percussively and uniformly agitating or vibrating the uppermost drum wall through means of the centrally disposed ridge-bar, to loosen the material adhering to its under inner surface.

In order to adjust the throw of the tapper arms, to increase or decrease their force, and to vary the quality of their whip-like 120 blows conformably to requirements, adjustment and bumper means are provided, of which a description follows:

Attached to the trip arm 24 is a bumper 30 in the form of a rubber disk, which bumper is designed to contact a headed screw 31 held in a screw threaded boss 32 and adjustable therein, the boss forming an integral part of a supporting arm 33 attached to the side of the "screen" frame. 130

A set nut 34 is provided for holding screw 31 in its adjusted position. The screw adjustment is made (see Fig. 3, dot-and-dash lines), so that the outer end of the 5 trip arm in its lower position is slightly spaced from the trip wheel 27, and in this position the outer ends 20^b of the tapper arms 20^a are correspondingly slightly spaced above the anvil-strips and normally sus- 10 tained in a non-strip bearing position. It has been found that the non-bearing sus- 15 tenion of the outer end of the arms 20^a and 24 in relation respectively to the strips and trip-wheel prevents a backward snap of the 20 arms after the strips have received their blows but allows the arms 20^a to vibrate, generally giving a series of tapping blows during a short arc of continued rotation of the drum. Inasmuch as the ends of the 25 tapper arms are normally spaced from the anvil-strips 20^a, the arms in their arrested downward movement, are sprung or flexed to give the whip-like blows to the said strips.

25 To increase or decrease the percussive effects of the tapper arms blows, these arms are provided with weights 36 adjustable thereon toward and from the free end thereof, which will vary the degree of vibration 30 of the arms with respect to the anvil-strips conformably to an efficient cleansing of the screen.

The features herein claimed are of extreme importance and have been found to 35 increase the output of the "screen" fifty per cent.

Having described my invention, I claim:

1. In a device of the class described, a 40 foraminous wall drum composed of frame sections, each section comprising a pair of clamping frames, each frame having a centrally disposed longitudinal bar, said frames and bar adapted to engage at opposite sides of and clamp screen fabric therebetween, 45 each of the outer of said frames having a plurality of bowed strips disposed at a right angle to the outermost longitudinal bar, said strips attached to said bar, bridging and spaced from said screening material, 50 and terminally attached to said frame, and an arm hingedly mounted and adapted to descend by gravity against any one of said cross strips.

2. In a device of the class described, a 55 rotatable drum formed of a plurality of frame units having screening material clamped thereacross, each frame providing a centrally disposed longitudinal bar extending the full length thereof, and contact- 60 ing said screen material, a plurality of bowed strips disposed cross-wise of said bar attached thereto bridging said screening material and attached to said bar and frame, arms unitarily swingable for simultaneously 65 striking all strips of each frame,

means for periodically raising said arms in a drum cycle, for descent by gravity to tap said strips, and bumper means for establishing a nonstrip bearing sustension of said arms, allowing arm vibration when said arms are tripped for percussively tapping said strips. 70

3. In a device of the class described, a rotatable screening drum composed of a plurality of frame units, each comprising a pair of frames, providing centrally disposed longitudinal bars, screening material clamped between said frames and bars, one of said bars forming an outwardly directed ridge, a plurality of bowed strips bridging 75 said screen, crossing said bar and attached to the bar at right angles thereto, and terminally fastened to opposite frame members, the corresponding strips of each frame being circumferentially aligned in planes of rotation of said drum, and means for simultaneously striking all strips of each frame when such frame is in its uppermost position. 80

4. In a device of the class described, a rotatable poly-faced drum, composed of frame units, each comprising a pair of rectangular sections designed to clamp screen fabric therebetween, a pair of centrally disposed longitudinal bars attached to each frame and extending the full length thereof, for clamping said screen therebetween, the outer of said bars forming a ridge across which and at right angles thereto are disposed a plurality of strips bridging said screen fabric and attached at their outer extremities to the sides of said outer section, the corresponding strips of each frame being circumferentially aligned, means for simultaneously striking the strips of each frame when a given frame is in its uppermost position, said means descending by the action of gravity, and adjustable buffer means for establishing a nonstrip bearing sustension of said strip-striking means, to allow vibration of the same after striking 100 said strips. 105

5. In a device of the class described, a drum providing a shaft for rotating the same, said drum formed of a plurality of frame units having screening material clamped thereacross, each frame providing a centrally disposed longitudinal bar contacting said screen material, a plurality of strips disposed cross-wise of said bar attached thereto and to said frame, corresponding strips of each bar being circumferentially alinged, when assembled to form the drum, arms unitarily swingable for simultaneously striking the strips of each frame, means for periodically tripping said arms in a drum cycle for descent by gravity, said means comprising a plurality of spring arms attached to a rotatable shaft, a trip arm at the end of said shaft engageable with the teeth of a ratchet wheel on said drum shaft, and 115 120 125 130

bumper means engageable with said trip arm and adjustable in relation thereto for establishing an arm nonstrip bearing suspension of said arms to allow vibrative movement of the same when tripped for percussively tapping said strips.

6. In a device of the class described, a frame for supporting a stretched screen fabric, a bar extending along the screen and secured at its opposite ends to said frame, said bar adapted to be vibrated for jarring the screen fabric, a yielding member ex-

tended transversely to the bar and connected therewith and to the frame, for yieldingly sustaining said bar, and means for percussively tapping said bar.

In witness whereof, I hereunto subscribe my name, as attested by the two subscribing witnesses.

GEO. M. STEDMAN.
